Patented Oct. 10, 1961

191,521

PRACTICE PUTTING DEVICE

William Anderson Baker, P.O. Box 812,
Hattiesburg, Miss.

Filed Dec. 8, 1959, Ser. No. 58,596

Term of patent 3½ years

(Cl. D34—5)

FIG. 2

FIG. 1

FIG. 1

FIG. 3

FIG. 1 is a perspective of a Practice Putting Device illustrating my new design;

FIG. 2, a top plan view thereof; and

FIG. 3, a front elevation.

I claim:

The ornamental design for a practice putting device, as shown.
